TRAFFIC SIGNAL

Filed May 27, 1931

FIG. 2.

FIG. 3.

Thomas R. Pavelsky
Inventor
By *Frank Reifer*
Attorney

UNITED STATES PATENT OFFICE

THOMAS R. PAVELSKY, OF ROCHESTER, NEW YORK

DESIGN FOR A TRAFFIC SIGNAL

Application filed May 27, 1931. Serial No. 40,003. Term of patent 14 years.

To all whom it may concern:

Be it known that I, THOMAS R. PAVELSKY, a citizen of the United States residing at Rochester in the county of Monroe and State of New York have invented a new, original and ornamental design for traffic signal of which the following is a specification: reference being had to the accompanying drawings, forming part thereof.

The object of this invention is to provide a new and ornamental design for a traffic signal or policeman.

In the drawings:

Figure 1 is a side elevation of the traffic signal showing an upright pedestal, which is

an octagon in cross section and tapers slightly from the bottom up. An upright shaft is mounted in the pedestal, which shaft supports a box substantially in the form of a cube, on the sides of which the lettering of the traffic signal can be displayed.

Figure 2 is a top plan view of the traffic signal.

Figure 3 is a horizontal section on the line 3x 3x of Figure 1.

I claim:

The ornamental design for a traffic signal as shown and described.

In testimony whereof I affix my signature.

THOMAS R. PAVELSKY.
